CLAIM

The ornamental design for an activity toy, substantially as shown and described.

DESCRIPTION

FIG. 1 is a left side elevational view of an activity toy showing my new design;

FIG. 2 is a right side elevational view thereof;

FIG. 3 is a front elevational view thereof, the rear elevational view being a mirror image thereof;

FIG. 4 is a top plan view thereof;

FIG. 5 is a bottom plan view thereof; and,

FIG. 6 is a sectional view taken along line 6-6 of FIG. 3. The broken lines illustrate unclaimed portions and form no part of the claimed design.

1 Claim, 3 Drawing Sheets(56)
